Attorney

UNITED STATES PATENT OFFICE.

FRED W. DOGE, OF CRESTON, IOWA.

EGG CARRIER.

Application filed June 4, 1924. Serial No. 717,793.

To all whom it may concern:

Be it known that I, FRED W. DOGE, a citizen of the United States, residing at Creston, in the county of Union and State 5 of Iowa, have invented a new and useful Egg Carrier, of which the following is a specification.

This invention relates to a device of that type generally known as an egg carrier, one 10 of the objects of the invention being to provide a structure of this character into which an egg filled carton of the usual cellular type can be inserted readily and held securely, certain portions of the carton co- 15 operating with peculiarly shaped surfaces of the carrier so as to provide cushions which will prevent the eggs from becoming broken in transit.

Another object is to provide a similar 20 means whereby the carton can be ejected readily from the carrier.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings the preferred form of the invention has been shown.

In said drawings—

35 Figure 1 is a plan view of the carrier, a portion thereof being shown in section to disclose a filled carton in position therein, a portion of the carton being also shown in section.

40 Fig. 2 is a section on line 2—2, Fig. 1.

Fig. 3 is an end elevation of the carrier.

Referring to the figures by characters of reference 1 designates a box-like carrier preferably formed of sheet metal such as 45 aluminum, this carrier having one open face, the top wall of which is preferably offset outwardly, as indicated at 2 and provided with apertures 3 for the reception of opposed portions of the retainer 4. This retainer is preferably formed of a piece of 50 resilient wire bent to rectangular form and having opposed nodes or offsets 5 adapted normally to extend into the openings 3 so as to prevent the retainer from moving outwardly to the position indicated by broken lines in Fig. 3. By pulling outwardly on

the retainer, however, the nodes can be caused to snap through the opening 3 so as to bring the inner portion of the retainer into the receiving space provided by the 60 offset 2.

The end wall of the carrier opposite the open end thereof is provided with an opening 6 sufficiently large to receive the fingers of the hand so that the carton contained in 65 the carrier can thus be shifted readily out of the open end thereof.

Suitably located on the top and bottom faces of the carrier are rounded projections 7 formed by pressing the metal outwardly 70 to produce recesses 8. These recesses are so located as to extend across the centers of the egg holding cells in a carton to be used in the carrier.

In the drawings, a carton of the ordinary 75 card-board type has been illustrated at 9 and this carton is provided with intersecting partitions 10 dividing the interior of the carton into separate egg receiving cells 11. The 80 ends of the partitions are adapted to bear against the walls of the carton while the end and side partitions are extended parallel with but spaced from the walls of the carton, thereby to leave air spaces 12 between said walls and the partitions as 85 shown. Thus it will be seen that when an egg E is placed in each cell 11, the ends thereof will engage the top and bottom of the carton at points directly opposite the recesses 8 and as these recesses form air 90 spaces between the egg engaging portions of the carton and the projections 7, it will be apparent that said portions of the carton will act as cushions to protect the eggs from breakage. The side and end partitions 10 will also act as cushions because 95 they are spaced from the adjoining walls of the carton as will be seen by referring to Fig. 1. When the retainer 4 is in normal position, it laps the exposed end of the carton and thus prevents it from being displaced relative to the carrier. With the retainer thus located and held by the nodes 5, the carrier can be shifted with little danger 100 of breaking the eggs therein. When it is desired to remove the carton the retainer 4 is pulled outwardly from the path of the carton 9 as indicated by broken lines in Fig. 105 3 and the fingers of the user are then forced through openings 6 and against the carton so as to force it from the open end of the carrier.

What is claimed is:—

1. An egg carrier including a box-like container having an open carton receiving end, there being an aperture in the other end of
- 5 the carrier for the reception of carton ejecting means, a carton retainer movably engaging the carrier adjacent the open end thereof, said retainer comprising a resilient member 30
10 slidable within spaced apertures in the carrier, and means upon opposed portions of the retainer and cooperating with the walls of the apertures for holding the retainer in carton retaining position.
2. An egg carrier including a box-like container having an open carton receiving end, there being an aperture in the other end of the carrier for the reception of carton ejecting means, a carton retainer movably engaging the carrier adjacent the open end thereof, 35
15 said retainer comprising a resilient member slidable within spaced apertures in the carrier, and means upon opposed portions of the retainer and cooperating with the walls of the apertures for holding the retainer in carton retaining position, said carrier being
20 offset to receive a portion of the retainer
25

when moved out of the path of the carton in the carrier.

3. An egg carrier including a box-like structure having an open end for the reception of a carton, and outwardly extended projections upon the top and bottom of the carrier forming recesses within the carrier adapted to bridge the egg engaging portions of the top and bottom of a carton within the carrier.

4. An egg carrier including a box-like structure having an open carton receiving end, there being an aperture in the other end of the carrier for the reception of ejecting means, rounded projecting portions upon the top and bottom of the carrier providing recesses within the carrier for bridging the egg engaging portions of the top and bottom of the carton within the carrier.

In testimony that I claim the foregoing as my own, I have hereto affixed my signature in the presence of two witnesses.

FRED W. DOGE.
